US00D523812S

(12) **United States Design Patent** (10) **Patent No.:** **US D523,812 S**
Brodin (45) **Date of Patent:** **** Jun. 27, 2006**

(54) **CONNECTOR FOR MULTI-CONDUCTOR CABLE**

(75) Inventor: **Hans Karl Johan Brodin**, Enebyberg (SE)

(73) Assignee: **Atlas Copco Tools AB**, Nacka (SE)

(**) Term: **14 Years**

(21) Appl. No.: **29/183,273**

(22) Filed: **Jun. 9, 2003**

(30) **Foreign Application Priority Data**

Dec. 9, 2002 (SE) 02-1757

(51) **LOC (8) Cl. 13-03**

(52) **U.S. Cl. D13/146; D13/147**

(58) **Field of Classification Search** ..... D13/133, D13/146, 147, 149, 154, 184, 199; 174/88 C; 439/314-316, 359, 362, 372

See application file for complete search history.

(57) **CLAIM**

The ornamental design for a connector for multi-conductor cable, as shown and described.

DESCRIPTION

FIG. 1 is a front perspective view of a connector for multi-conductor cable, showing my new design;

FIG. 2 is a front elevation view thereof; and,

FIG. 3 is a rear perspective view thereof.
